US00D821534S

(12) **United States Design Patent** (10) **Patent No.:** **US D821,534 S**
(45) **Date of Patent:** **** Jun. 26, 2018**

(54) **FIREARM MAGAZINE LOADER/UNLOADER**

(71) Applicant: **William Christopher Couie**, Vidalia, LA (US)

(72) Inventor: **William Christopher Couie**, Vidalia, LA (US)

(**) Term: **15 Years**

(21) Appl. No.: **29/607,576**

(22) Filed: **Jun. 14, 2017**

(51) **LOC (11) Cl.** **22-01**

(52) **U.S. Cl.**

USPC **D22/108**

(57) **CLAIM**

The ornamental design for a firearm magazine loader/unloader, as shown and described.

DESCRIPTION

FIG. 1 is a top front left side perspective view of a firearm magazine loader/unloader;

FIG. 2 is a top front right side perspective view thereof;

FIG. 3 is a bottom rear right side perspective view thereof;

FIG. 4 is a right side view thereof;

FIG. 5 is a rear view thereof;

FIG. 6 is a left side view thereof;

FIG. 7 is a front view thereof;

FIG. 8 is a top view thereof; and,

FIG. 9 is a bottom view thereof.

1 Claim, 6 Drawing Sheets
